SAFETY CLIP SNAP FOR BRACELETS
AND THE LIKE

Victor Salvo and Vincent Salvo, New York, N. Y.

Application June 6, 1935, Serial No. 25,198

5 Claims. (Cl. 24—73)

This invention relates to new and useful improvements in a safety clip snap for bracelets and the like.

The invention has for an object the construction of an article as mentioned which is characterized by an upper jaw for supporting an ornament and having a projection at the center of its inner end, and a lower jaw of two layers in which the lower layer has its inner end formed with a pair of spaced bearings located on opposite sides of said projection and pivotally connected therewith by a pintle pin.

As another object the invention contemplates the arrangement of a cylindrical portion on the outer end of the lower jaw continuing into the upper layer thereof and extending inwards and over the lower layer and terminating in a finger extending beneath said projection and through the lower layer to a position in the vicinity of the pivotal connection of the jaw members to act as a stop for limiting the opening of the jaw.

Still further the invention proposes the provision of a cam portion on the projection and engaging against said finger for holding the top jaw member either in the closed or the opened position.

Furthermore, the invention proposes the association of links with said safety clip snap, each link to have a transverse rod associated with a portion of the safety clip snap in such a manner so as to prevent the accidental disengagement of these parts.

Another object of this invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a fragmentary sectional view as though taken on the line 1—1 of Fig. 2.

Fig. 2 is a plan view of a safety clip snap device constructed according to this invention and shown associated with a pair of links.

Fig. 3 is a bottom elevational view of Fig. 2.

Fig. 4 is an end elevational view looking in the direction of the line 4—4 of Fig. 2.

Fig. 5 is a sectional view as though taken on the line 5—5 of Fig. 4, but illustrating the clip snap in an open position.

Fig. 6 is a view similar to Fig. 5 but illustrating the clip snap in its closed position.

Fig. 7 is a plan view of another form of safety clip snap device associated with a belt.

Fig. 8 is a similar view to Fig. 7 showing the safety clip snap device associated with a shoulder strap of a garment.

The safety clip snap for bracelets, belts, shoulder straps, etc., according to this invention, comprises an upper jaw member 10 for supporting an ornament 11, and having a projection 12 at the center thereof at its inner end. A lower jaw member 13, consisting of layers 13^a and 13^b, has its lower layer formed at its inner end with a pair of spaced bearings 14 located on opposite sides of the projection 12. A pintle pin 15 engages through the bearings 14 and the projection 12 for pivotally connecting the jaw members.

A cylindrical portion 16 is formed on the outer end of the jaw member 13 and constitutes the junction between the upper and lower layers.

The upper layer 13^a of the jaw member extends inwards and over the lower layer and terminates in a finger 17 which extends beneath the projection 12 and which passes through an opening 18 formed in the lower layer. The finger 17 terminates in the vicinity immediately behind the pivot of the jaw members and is adapted to limit the opening of the jaw members, as clearly shown in Figs. 1 and 5. It should be noted that when the jaw members are moved to the open position, the ornament 11 strikes against the end of the finger. This limits the pivoting of the jaw members.

The projection 12 is formed with a cam portion 12^a which engages against the base end of the finger 17. This cam portion 12^a functions to maintain the jaw members either in the open or in the closed positions. For example, in Figs. 1 and 5 the cam portion 12^a is shown engaged against the base portion of the finger 17 to maintain the open position. In Fig. 6 the cam portion 12^a is shown moved around through substantially 60° to a position in which it engages a different portion of the finger 17 to maintain the jaw members in the closed position. The free end of the jaw member 10 is formed with a hook portion 19 adapted to engage the outer contour of the cylindrical portion 16 for latching the jaw members together. This is clearly shown in Fig. 6.

The clip snap device is associated with a bracelet or similar object which is partially indicated on the drawing by the links 20 and 21. Each of these links is formed with a transverse bar 22. The transverse bar 22 from the link 20 engages through the cylindrical portion 16 so that the clip

is permanently but pivotally connected with this link. The transverse bar 22 of the link 21 engages in the space between the jaws and has a natural tendency, when the bracelet is worn to assume a position at the inner end of the jaw, as clearly shown in Fig. 1.

If the jaw members accidentally open the transverse bar 22 of the link will be maintained in its engaged position in the jaw because the jaw members are limited to open only through substantially 60°. If the link 21 does move towards the open end of the jaw, it will still be restrained from disconnecting the jaw member by reason of the transverse bar 22 coming in contact with the bent end 19 of the upper jaw member.

In Fig. 7 a different shape of the safety clip snap device is shown to be attached to the ends 20', 21' of a belt 23 and in Fig. 8 to a garment 20" and shoulder strap 21" to permit ready locking and separation of same.

While we have illustrated and described the preferred embodiment of our invention, it is to be understood that we do not limit ourselves to the precise construction herein disclosed and the right is reserved to all forms coming within the scope of the invention as defined in the appended claims.

Having thus described our invention, what we claim as new, and desire to secure by United States Letters Patent is:—

1. In a safety clip snap for bracelets and the like, an upper jaw member for supporting an ornament and having a projection on the center of its inner end, a lower jaw member of two layers, and in which the lower layer has an opening and its inner end formed with a pair of spaced bearings located on opposite sides of said projection, a pintle pin through said bearings and projection for pivotally connecting the jaws, and a cylindrical portion on the outer end of the lower jaw and continuing into said upper layer and extending inwards over the lower layer and terminating in a finger extending beneath said projection and through the opening in the lower layer to a position in the vicinity of said pivotal connection to act as a stop for limiting opening in said jaw members.

2. In a safety clip snap for bracelets and the like, an upper jaw member for supporting an ornament and having a projection on the center of its inner end, a lower jaw member of two layers and in which the lower layer has an opening and its inner end formed with a pair of spaced bearings located on opposite sides of said projection, a pintle pin through said bearings and projection for pivotally connecting the jaws, and a cylindrical portion on the outer end of the lower jaw and continuing into said upper layer and extending inwards over the lower layer and terminating in a finger extending beneath said projection and through the opening in the lower layer to a position in the vicinity of said pivotal connection to act as a stop for limiting opening in said jaw members, the free end of the upper

jaw member being formed with a hook portion adapted to engage said cylindrical portion for holding the jaw members closed.

3. In a safety clip snap for bracelets and the like, an upper jaw member for supporting an ornament and having a projection on the center of its inner end, a lower jaw member of two layers and in which the lower layer has an opening and its inner end formed with a pair of spaced bearings located on opposite sides of said projection, a pintle pin through said bearings and projection for pivotally connecting the jaws, a cylindrical portion on the outer end of the lower jaw and continuing into said upper layer and extending inwards over the lower layer and terminating in a finger extending beneath said projection and through the opening in the lower layer to a position in the vicinity of said pivotal connection to act as a stop for limiting opening in said jaw members, and a cam portion on said projection engaging against said finger for holding the jaws in the closed or in the open positions.

4. In a safety clip snap for bracelets and the like, an upper jaw member for supporting an ornament and having a projection on the center of its inner end, a lower jaw member of two layers and in which the lower layer has an opening and its inner end formed with a pair of spaced bearings located on opposite sides of said projection, a pintle pin through said bearings and projection for pivotally connecting the jaws, and a cylindrical portion on the outer end of the lower jaw and continuing into said upper layer and extending inwards over the lower layer and terminating in a finger extending beneath said projection and through the opening in the lower layer to a position in the vicinity of said pivotal connection to act as a stop for limiting opening in said jaw members, said bearings comprising cylindrical turned portions from the material of the lower jaw member.

5. In a safety clip snap for bracelets and the like, an upper jaw member for supporting an ornament and having a projection on the center of its inner end, a lower jaw member of two layers and in which the lower layer has an opening and its inner end formed with a pair of spaced bearings located on opposite sides of said projection, a pintle pin through said bearings and projection for pivotally connecting the jaws, a cylindrical portion on the outer end of the lower jaw and continuing into said upper layer and extending inwards over the lower layer and terminating in a finger extending beneath said projection and through the opening in the lower layer to a position in the vicinity of said pivotal connection to act as a stop for limiting opening in said jaw members, and an ornament attached on the outer side of said upper jaw member and adapted to have its end engage the end of said finger for limiting pivoting of the jaws to the open position.
